UNITED STATES PATENT OFFICE.

EVERETT H. BARNEY, OF SPRINGFIELD, MASSACHUSETTS.

SKATE.

SPECIFICATION forming part of Letters Patent No. 248,272, dated October 18, 1881.

Application filed March 25, 1881. (No model.)

To all whom it may concern:

Be it known that I, EVERETT H. BARNEY, a citizen of the United States, residing at Springfield, county of Hampden, and State of Massachusetts, have invented new and useful 5 Improvements in Skates, of which the following is a specification.

This invention relates to the details of the construction of locking and adjusting devices 10 interposed between the sole and heel clamping mechanism of a skate, to cause the sole and heel clamps thereof to be properly operated, the object being to provide devices for the above-mentioned purpose which can be removed from and replaced upon the skate without the aid of any tools whatever, which are 15 powerful to fasten the clamps, easy of adjustment to varying sizes of shoes, and can be quickly operated by the hand alone.

20 In the drawings forming part of this specification, Figure 1 is a plan view of a skate embodying my improvements. Fig. 2 is a plan view of the bottom of the skate, with the runner in the rear of the sole-plate broken away 25 and the parts under the heel-plate shown partly in section. Fig. 3 is a plan view of the sole-clamps detached from the sole-plate. Fig. 4 is a view of the pivoted locking-levers detached from the skate, with the outer edge of its pivot 30 shown in dotted lines. Fig. 5 is a longitudinal sectional view of the heel-clamp and of the rear end of the screwed clamp-rod. Fig. 6 is an isometric view of one of the sole-clamps. Fig. 7 is a vertical section of the clamp and 35 lever-pivot. Fig. 8 is a vertical section of the clamp-rod nut and rear locking-lever pivot.

In the drawings, A is the sole-plate, and B the heel-plate. c is the runner. d d are the sole-clamps. e is the heel-clamp. f is the 40 screwed clamp-rod. h i are the pivoted locking-levers. n is the clamp and lever pivot, and o is the clamp-rod nut and rear locking-lever pivot. s is a stud set in the heel-clamp e.

Like letters refer to like parts in the several 45 figures.

The construction of the sole-plate and sole-clamps and the means for securing the latter to said sole-plate by studs having elongated heads, as shown herein, are substantially the 50 same as those shown in my patent of May 2, 1876, to which reference may be had; and the

construction of the heel-plate-supporting brackets shown herein, whereby they spread under said plate and form a longitudinal chamber thereunder for the reception of the hollow 55 shank of the heel-clamp, is also substantially like that shown in said patent.

The heel-clamp e is constructed with a longitudinal shank, e', which fits into the said chamber under the heel-plate, and has two vertical 60 clamp-dogs projecting upward on one end, which, when the heel-clamp is operated, are forced against the rear of the boot-heel. The said shank e' is hollowed out to let the clamp-rod f pass through it, as shown. 65

Projecting upward from the bottom of said shank e' is a stud, s, which enters a groove, t, cut around that part of the clamp-rod which operates within said shank, so that when said rod is unscrewed and drawn back it carries the 70 heel-clamp back with it.

The ends of the sole-clamps d d, which meet in the rear of the sole-plate, are so formed as to overlap each other, and are perforated to receive the pivot n, upon which they swing as 75 the clamp-jaws move to and from the edge of the sole-plate. The said pivot n is perforated transversely to let the end of the clamp-rod f pass through it, as shown in Fig. 2.

The locking-lever h is made in the form 80 shown, having one end perforated to permit of passing the shank part of the clamp-rod nut through it, and its opposite end is adapted to be hooked around the shank part of the pivot n, as shown. 85

The locking-lever i, provided with the thumb-piece i², is pivoted upon the pivot n, as shown, and is also pivoted to the extremity of the hook end of lever h, so that when the end i² of lever i is swung from the position shown in 90 Fig. 4 to that shown in Fig. 2, lever h becomes hooked around pivot n with lever i.

The screwed clamp-rod f is screwed through the nut o, upon which lever h has been placed, so that the latter is held thereon between said 95 rod and the under side of said nut, and the smaller plain end of said rod is passed through the hole in the shank of the clamp and lever-pivot, holding the hooked end of lever i between it and the under side of the head on said 100 pivot, but leaving room, also, to hook the end of lever h around it, as aforesaid.

A ring, x , is secured to the outer end of said rod f , by means of which it may be conveniently turned in its nut o , to operate to adjust the sole and heel clamps to different sizes of 5 boots, as hereinafter set forth, and to act as a stop against heel-clamp e .

The operation of my improved skate-fastening devices is as follows: The end i^2 of lever i is swung around toward the rear end of the 10 sole-plate A, disengaging the hook of lever h from the pivot n and moving the latter and nut o farther apart. If the sole-clamps stand near the edge of the sole-plate and the heel-clamp near the rear end of the heel-plate when 15 lever i is swung around, as just described, the effect thereof will be to move said clamps away from the said sole and heel plates, so as to permit of placing the heel and sole of a boot upon the skate and within the upstanding portions 20 of said clamps. To move said upstanding portions of said clamps up against the edges of the boot-sole and against the rear of the heel, rod f is turned to screw it into nut o by taking hold of ring x , and by so doing the heel-clamp 25 is brought to a stand against the heel and nut o is drawn back, taking with it the pivot n , which slides on the smooth end of rod f , and so drawing upon the ends of the sole-clamps d , which are attached to said pivot, as to cause 30 them to slide upon the studs which hold them to the sole-plate and force their upstanding portions up against the edges of the boot-sole. The skate-fastenings are now adjusted to that sized boot, so that the skate may be put onto 35 it, and the fastening of it to the boot is completed by turning lever i back to the position shown in Fig. 1. This draws nut o and pivot n toward each other and forces the sole and heel clamps against the boot with great power, 40 particularly at the period in the movement of the parts when the hooked end of lever h is about engaging with pivot n , upon which it is finally hooked, thus holding the said clamps rigidly against the boot and securing the skate 45 firmly to the latter. It is only necessary to

turn the end of lever i again toward the sole-plate to take the skate off.

The skate-fastening devices herein shown and described are easily detached from the skate as follows, for the purpose of cleaning or 50 repairing: The rod f is screwed back quite out of nut o , and, with the heel-clamp e , may now be drawn quite out from under the heel-plate, entirely freeing them from the skate. Nut o and pivot n are now taken off from levers h 55 and i , and from the ends of the sole-clamps d , permitting the latter to be so turned upon the pivots which hold them up against the sole-plate as to bring the long sides of their heads in a line with the slots in the said clamps, when 60 the latter will drop away from the sole-plate. The parts are replaced in the same order.

If desired, the fastening devices herein shown and described may be employed for securing the sole-plate only to the boot by discarding 65 the particular heel-clamp herein shown and using some other heel-fastening in its stead, and in such a case allowing the ring x on the end of rod f to abut against the ends of the heel-supporting brackets when the levers h 70 and i are operated, as above described, to draw the sole-clamps against the edges of the boot-sole.

I do not claim, broadly, sliding toe and heel 75 clamps and levers, whereby the same may be drawn together and locked or separated; but

I claim—

1. In combination with the screw clamp-rod f , a pivot, n , on said rod, joining the sole-clamps thereto, a nut, o , thereon, jointed to a lever, h , 80 and a lever, i , pivoted to the lever h and turning on the pivot n , substantially as set forth.

2. The heel-clamp e , provided with the stud s , in combination with the clamp-rod f , having the annular groove t around it, substantially 85 as and for the purpose set forth.

EVERETT H. BARNEY.
